June 11, 1969. This application June 15, 1970, Ser.
No. 23,477

Term of patent 14 years

Int. Cl. D26—03

U.S. Cl. D48—31

FIG. 1 is a front elevational view of a luminaire embodying my new design;

FIG. 2 is a top plan view thereof;

FIG. 3 is a side elevational view thereof;

FIG. 4 is a bottom plan view thereof;

FIG. 5 is a rear elevational view thereof; and

FIG. 6 is a view of the luminaire as observed in the direction of arrow 6 in FIG. 3.

The standard is broken away in FIGS. 1, 3 and 5 to indicate indeterminate length.

This is a continuation-in-part of design application Ser. No. 17,648, filed June 11, 1969, and now abandoned.

I claim:

The ornamental design for a luminaire, as shown and described.
